AUTOMATIC SIZING SELECTOR

BACKGROUND OF THE INVENTION

This invention relates to an automatic sizing selector and, more particularly, to a device for automatically gauging and sorting eyelets used in the manufacture of all-glass multiple glazed window units.

Eyelets which are to be gauged and sorted, within the contemplation of this invention, include frustoconical shaped elements having their conical surface coated with a low melting point glass frit and a cylindrical opening in the center thereof so that the axis of the cylinder coincides with the axis of the frustum shaped element. The construction and use of these elements is fully disclosed in U.S. Pat. No. 2,984,294, issued July 14, 1959 to F. R. Prescott. The foregoing patent is assigned to the assignee of the present invention and the disclosure thereof is incorporated herein by reference.

In the past, eyelets of the type disclosed in the above-mentioned patent were manually sized and sorted individually, in accordance with predetermined ranges or acceptable tolerance deviations in their outside diameters. This was a tedious, time- and labor-consuming operation which was obviously subject to human error. Accordingly, the present invention is directed toward providing an automatic sizing selector for such eyelets to eliminate the foregoing deficiencies of the prior-art technique. Also, this invention is directed toward providing a suitable device for sizing or gauging and sorting eyelets which is simple in operation and construction, requires little or no maintenance and is inexpensive to fabricate, install and use.

The above and other objects, features and advantages of this invention will become more apparent from the description that follows, when taken in conjunction with the drawings, in which:

FIG. 1 is a right side view of a device constructed in accordance with this invention and in which the size selector plates are shown in an open position;

FIG. 2 is a plan view, taken along the line A-A of FIG. 1, showing the size selector plates in a closed position; and

FIG. 3 is a plan view, also taken along the line A-A of FIG. 1, showing the size selector plates in an open position.

As illustrated in the drawings, the automatic sizing selector 10 of this invention comprises a sloping series or succession of size selector plates 12. Size selector plates 12, as shown, are rotatably mounted by means of their horizontally disposed axles or spindle rods 16 being suitably journaled in spaced, vertically arranged plates 18 and 20. Spindle rods 16 extend through plate 20 and have pinion gears 22 affixed to their extended free ends. Supported by vertical plate 20 is a suitable guideway 24, such as a U-channel member, which carries and guides a rack member 26 that operatively engages gears 22 for the purpose of simultaneously rotating all of the size selector plates 12. Moreover, rack 26 is connected to a device, such as fluid cylinder 28, which is actuated in desired timed sequence by any suitable means, e.g., a solenoid-operated valve energized through a timer or a microswitch actuated by movement of an eyelet coating machine, to reciprocate rack 26 and rotate gears 22, thereby rotating size selector plates 12 to a desired open and closed position.

As illustrated in FIG. 2, in their closed position, size selector plates 12 are brought into coplanar, edge-abutting relation so that their upper surfaces form an essentially continuous, downward sloping planar surface. On the other hand, as illustrated in FIG. 3, in their open position, size selector plates are rotated to a position where the trailing edge 30 of each plate is elevated above the horizontal, e.g., preferably to an angular position of about 30° to 45° above a horizontal plane through each of their respective axes of rotation.

Disposed beneath or subjacent the above-described size selector plate assembly, there is depicted in FIG. 1 a sorting container 32 which is also shown as being preferably attached or made integral with the size selector plate assembly. Sorting container 32 is essentially a rectangular enclosure, one side 14

of which is preferably composed of transparent material for viewing the contents thereof. Container 32 is subdivided into compartments or bins 34 by a series of parallel walls 36 extending between plates 18 and 20 and suitably spaced laterally of each other to provide a bin subjacent the leading edges 38 of at least each of the size selector plates 12 as they are rotated from a closed position to an open position. In the embodiment shown, one additional bin 34 is provided forward of the bottom or last size selector plate 12 and, as will be better understood by that which follows, this bin collects eyelets of the smallest outside diameter. For the purpose of facilitating removal of eyelets from bins 34, as desired, container 32 is provided with slide plates 40 covering an opening in the bottom of each bin 34. As will be understood, sliding the plates 40 with respect to their supporting angle flanges 42 will permit the eyelets to drop from bins 34.

As best seen in FIGS. 2 and 3, size selector plates 12 have affixed on the upper surface thereof a plurality of gauge rods or bars 44. In the embodiment shown, each plate 12 is provided with three such gauge rods, with one being located centrally of the plate and extending from the leading to the trailing edge thereof and the other two rods similarly extending from the leading to the trailing edge in spaced converging relation toward the center rod. Each of the gauge rods are preferably rounded along their opposed side edges. Also, the spacing between each converging rod and the center rod at the trailing edge of plate 12 is identical as regards any given plate but diminishes or is slightly less for each successive plate in a direction from top to bottom or downward along the sloping succession of size selector plates. In addition, as shown, affixed with respect to each plate 12 and overlying the gauge rods 44 is a holdown plate 46 which preferably is coextensive with about the lower or trailing two-thirds of each plate 12.

Also, as best shown in FIGS. 2 and 3, the trailing edge of each plate 12 has a notch 48 between the center gauge rod and each of the converging gauge rods. Notches 48 on both sides of the center gauge rod are aligned with regard to each successive plate. Affixed to the front of the size selector assembly and extending parallel to the size selector plates in their closed position are a pair of spaced, parallel bars or blades 50, each of which is in vertical alignment with one of the series of notches 48 disposed on either side of the center gauge rods. The spacing of blades 50 from plates 12 is such that, as plates 12 are simultaneously rotated into their open position, each plate is intercepted by one of the blades 50 seating in each of an aligned series of notches 48.

Turning now to the mode of operation of the above-described device, a pair of eyelets are released simultaneously from a machine (not shown) which prepares the eyelets for use by applying a frit coating to their conical surfaces. The eyelets are then gravity fed, largest diameter down and along separate paths, down a tubular, rectangular chute 52, wherein the separate paths are defined between sidewalls 54 and 56 and a center partition wall 58. As shown, center partition wall 58 is in alignment with center gauge rods 44. Thus, as the eyelets exit from chute 52, each eyelet is laterally confined in its respective separate path between the center gauge rod of the top plate and one of the converging gauge rods thereof. After each eyelet passes along its path a short distance, it is also vertically confined between holdown plate 46 and size selector plate 12 to prevent the eyelet from inverting and/or tipping out of its desired confined path of travel. The top or uppermost opening between the center gauge rod and each of the converging gauge rods on each size selector plate 12 is wide enough to catch and guide the piece to the bottom or lowermost opening therebetween, which has been narrowed to the desired size to allow only the eyelet units to pass that are desired to go to the next smaller size.

Starting at the top plate, the throats or openings between the center gauge rod and each of the converging gauge rods are set to hold the largest eyelet unit desired, and each of the pairs of gauge rods on each size selector plate down in succession is set to hold the next largest unit desired. Any eyelet unit

that passes all of the throats or gauge openings is immediately deposited in the collector bin 34 that is located forward of the bottom or last size selector plate 12. As indicated, the gauge rods are preferably of a rounded shape along at least their opposed surfaces to allow a tapered eyelet unit, disposed with its largest diameter against a size selector plate 12, to snug partly under the bottom spread of the rods, thereby holding the unit to be sized down against the metal plate 12 and forcing each unit to be indexed at the same level while allowing only point contact of the rounded rods at the throat between the gauge rods. Moreover, by varying the size of the rods and/or the radius used, the units can be gauged or sized at any elevation along the side of the unit that is desired.

After each of an initial pair of eyelets is sized as aforesaid, all of the size selector plates 12 are simultaneously rotated, in a clockwise direction as seen in FIG. 1, until notches or grooves 48 fork over blades 50. Blades 50 will force any unit out that might want to stick in the sizing gates or throats, thus positively causing the selector to be emptied and ready to receive the next unit to be sized with all stations available for each operation. As will be understood, the sized units are deposited in their respective collector bins 34 after tipping off the rotated leading edge of one of the size selector plates 12, and immediately thereafter the size selector plates are automatically returned to their closed position in preparation for sizing and sorting the next pair of units.

While a preferred embodiment of this invention has been illustrated and described, it will be understood that various changes and modifications may be made within the scope of the appended claims without departing from the spirit of the invention.

I claim:

1. An automatic sizing selector comprising a sloping series of size selector plates mounted to rotate about horizontal axes from a closed, edge-abutting position to an open, parallel-spaced position, gauge means affixed relative to the upper surface of said plates and mounted to rotate therewith, means to automatically and simultaneously rotate said plates in timed sequence between said positions and collector means for receiving and retaining units sized by said size selector plates according to selected desired sizes.

2. An automatic sizing selector according to claim 1 wherein each size selector plate has affixed to the upper surface thereof at least a pair of spaced, converging gauge rods

45

which extend from a leading edge to a trailing edge of said plate.

3. An automatic sizing selector according to claim 1 wherein each size selector plate has affixed to the upper surface thereof at least three gauge rods, with one gauge rod being located centrally of the plate and extending from a leading to a trailing edge thereof and the other two gauge rods similarly extending from said leading to said trailing edge in spaced, converging relation toward said center gauge rod.

10 4. An automatic sizing selector according to claim 3 wherein said gauge rods are rounded along their opposed side edges.

5. An automatic sizing selector according to claim 4 wherein each size selector plate has a holdown plate affixed 15 relative thereto, in overlying relation with respect to said gauge rods and spaced parallel relation with respect to said selector plate.

6. An automatic sizing selector according to claim 3 wherein each size selector plate has its trailing edge notched 20 between each adjacent pair of gauge rods to provide two aligned series of notches and a pair of spaced, parallel blades are affixed to said sizing selector and spaced from each said size selector plate so that, as the size selector plates are simultaneously rotated to said open position, each plate is intercepted by one of said blades seating in each of an aligned series of said notches.

7. An automatic sizing selector according to claim 6 wherein each size selector plate is simultaneously rotated between said closed and said open position by means of a rack 30 operatively associated with a gear affixed to each said size selector plate.

8. An automatic sizing selector according to claim 7 wherein said rack has connected thereto said means to actuate said rack in timed sequence.

9. An automatic sizing selector according to claim 3 wherein the spacing between each said converging gauge rod and said center gauge rod is identical as regards each size selector plate and said spacing diminishes for each successive size selector plate in a direction downward along said sloping 40 series of size selector plates.

10. An automatic sizing selector according to claim 9 wherein said gauge rods are rounded along their opposed side edges.
